UNITED STATES PATENT OFFICE.

JAMES HAMILTON JOHNSTON, OF RAYNE, LOUISIANA, ASSIGNOR TO STAMM-SCHEELE MANUFACTURING CO., LIMITED, OF RAYNE, LOUISIANA.

CENTRIFUGAL PUMP.

Application filed January 12, 1927. Serial No. 180,655.

My invention relates to the art of centrifugal pumps and particularly to that type in which the pump is suspended or set into a well casing and embodies an impeller 5 with a line shaft enclosed in a suitable casing through which the bearing lubricant is passed and which protects the bearings from sand and detritus. Usually such pumps are made with the line shaft, the shaft casing 10 and the discharge casing concentrically arranged and composed of a series of sections with shaft bearings located at the juncture of the casing sections, the bearings being composed of spiders carried by the discharge casing and screw coupled with the adjacent line shaft casing sections with provision for placing the line shaft casing sections under longitudinal tension to maintain the alignment of the bearings; the 20 bearings in some cases have a limited sliding fit in the discharge casing to allow for expansion and contraction due to temperature changes and for other reasons.

I have found that the construction above outlined possesses some objectionable features from the standpoint of manufacture and assembly.

My invention, therefore, has for its object to reduce the cost of manufacture, to so construct the bearing spiders, the discharge casing sections and the line shaft sections as to enable the manufacturing cost to be lowered, to enable the pump to be assembled with greater convenience, to provide for a perfect arrangement of the shaft bearings, shaft casing and discharge casing, section-by-section, as the parts are assembled, to obtain a sealing of the line shaft casing without the necessity of screw coupling it 35 with the bearings, and to provide for expansion and contraction due to temperature variation without causing the bearings to undergo a sliding movement with respect to their supports.

With other objects that will be clear to those skilled in the art the invention resides in those novel features of construction, combination and arrangement of parts, all of which will be first fully described, 50 then be particularly pointed out in the appended claims, reference being had to the accompanying drawings, in which:—

Figure 1 is a vertical half side elevation and half central longitudinal section of a pump employing my invention.

Figure 2 is an enlarged central vertical longitudinal section of the upper end of the same.

Figure 3 is an enlarged detail vertical longitudinal section of two bearing spiders 60 and the associated parts before the uppermost well casing section is bolted down.

Figure 4 is a similar view after the sections have been bolted together and showing how the packing is compressed at the 65 ends of the line shaft casing sections during the act of clamping the said casing sections together.

In the drawings in which like numerals of reference designate like parts in all the 70 figures, 1 represents the well casing which is provided with the usual cover 2 on which the pump head 3 is mounted. The pump head 3 carries the usual water jacketed head bearing 4 in which the head section 10 of 75 the line shaft is journalled, that section carrying the usual thrust plate 5. A thrust bearing 6 is provided and a drive pulley 7.

Oil is transmitted to the bearings through 80 a tube 8 and an air vent 9 is provided in the packet of the head bearing for the usual purposes. 11 designates the impeller adjusting nuts screwed on the head shaft section 10.

12 designates the impellers mounted with 85 in the impeller casing 13 on a stub shaft 14, the casing being provided with a bearing neck 15 in which is a bushing 16 for the stub shaft. The stub shaft is coupled to the line shaft (the line shaft being made in 90 sections coupled together as at 18) by a suitable coupler 18.

19 represents the discharge casing which is provided with the usual coupling flanges 20 (secured to the casing sections in any desired manner as for instance by threading). 95

All of the foregoing parts may be of the usual construction except that the coupling flanges 20 are recessed at 21 to receive the 100 rims 23 of the bearing spiders 22, the bearing spiders having bearing portions 24 for the line shaft. These bearing portions 24 at their upper and lower ends are milled to provide grooves 25 to receive the ends of the line shaft casing sections 27 and to 105 receive suitable packing rings 26 composed of cork, asbestos, rubber or any other suitable material.

The lower end of the lowermost line shaft casing section 27 has a pressed fit onto the 110

upper end of the neck bearing bushing 16.

The head bearing 4 has a downwardly extended portion 28 bored to receive the upper end of the uppermost line shaft casing 5 section and counterbored to receive suitable packing rings 29 and a gland nut 30 in order to enable a water seal to be effected at this place.

In practice the length of the line shaft 10 casing sections is so designed with relation to the discharge casing sections and to the bearing spiders that when the parts are brought together and before the discharge casing sections are clamped home (see Figure 3), the packing rings 26 will be engaged by the ends of the line shaft casing sections but will not be under compression. However, when the discharge casing sections are bolted tight the bearings will be brought 20 closer together with the result that the packing rings 26 will be placed under compression and effect a tight seal. By reason of the more or less resilient nature of the packing rings 26 variations in the expansion of 25 the line shaft casing over that of the discharge casing will be taken up in the packing rings 26, it being understood, of course, that this variation ordinarily is but slight.

The depth of the grooves 25 and the thickness 30 of the packing rings 26 may be varied to suit conditions met with in practice, it being understood, of course, that the deeper the grooves and deeper the packing rings the greater allowance for variations in expansion of the pipe sections is provided for.

In assembling the pump the impeller unit including the impeller and impeller casing is assembled and the first line shaft section is coupled to the impeller stub shaft. Next 40 the lower discharge casing section and the lower line shaft casing section are put into position, after which the first bearing spider is set in place. Of course, at this time the rim of the bearing spider will not seat down 45 tight on the lowermost flange of the discharge casing. After this the next line shaft section, discharge casing section and line shaft casing section are put in position and upon bolting the flanges of the two discharge 50 casing sections together they will effect a tight grip of the rim of the bearing spider and at the same time force it downwardly to an extent sufficient to compress the lowermost packing ring 26 and effect a 55 tight seal of the lowermost line shaft casing section. In a similar way, the upper sections of the line shaft, line shaft casing, discharge casing and bearings are assembled to the top of the well when the pump head, 60 parts are assembled in the usual manner, thus completing the assembly and placing the pump in condition for operation.

From the foregoing description, taken in connection with the accompanying drawings, it is thought that the complete con-

struction, operation and advantages of my invention will be clear to those skilled in the art to which it relates.

What I claim is:

1. In centrifugal pumps, a sectional discharge casing, line shaft bearing spiders secured between adjacent sections of said casing, a line shaft and line shaft casing sections located between adjacent bearing spiders, said bearing spiders including bearing members having grooved ends to receive the ends of the line shaft casing sections, and packing in the grooves.

2. In centrifugal pumps, a sectional discharge casing, line shaft bearing spiders secured between adjacent sections of said casing, a line shaft and line shaft casing sections located between adjacent bearing spiders, said bearing spiders including bearing members having grooved ends to receive the ends of the line shaft casing sections, and packing in the grooves, said line shaft casing sections being of such length relative to the discharge casing sections that when the discharge casing sections are secured together the bearing spiders will be drawn toward the line shaft casing ends to compress the packing.

3. In centrifugal pumps, wherein is provided a line shaft, an impeller and its casing, and a pump head; a sectional discharge casing having coupling flanges at the ends of the sections and means to draw said flanges together, said flanges being recessed, a set of line shaft bearing spiders with portions held in the recesses of the flanges, and portions located adjacent the line shaft and provided with recesses, packing material in said last named recesses, and line shaft casing sections set into said last named recesses and engaging said packing.

4. In centrifugal pumps wherein is provided a line shaft, an impeller and its casing, and a pump head; a sectional discharge casing having coupling flanges at the ends of the sections and means to draw said flanges together, said flanges being recessed, a set of line shaft bearing spiders with portions held in the recesses of the flanges, and portions located adjacent the line shaft and provided with recesses, packing material in said last named recesses, and line shaft casing sections set into said last named recesses and engaging said packing, said line shaft casing sections being of a length whereby when the bearing spiders are clamped tight between adjacent flanges they will compress the packing to effect a seal.

5. In centrifugal pumps of the kind employing an impeller, a line shaft, a sectional discharge casing and a sectional line shaft casing, shaft bearing spiders having rims rigidly secured to the discharge casing and having shaft bearings provided with shaft casing receiving grooves, packing elements

in said grooves against which the ends of the shaft casing engage, said shaft casing sections being so proportioned that adjustment of the securing means will apply compression force between pairs of bearings and the intervening shaft casing sections and packing elements substantially as and for the purposes specified.

6. In combination with the discharge 10 casing, the sectional line shaft casing and the shaft bearing spiders of a centrifugal pump; of means to secure the spiders rigidly to the discharge casing and cause them to press toward the ends of the adjacent shaft 15 casing sections, and yieldable bodies interposed between said ends and said bearing spiders to effect a seal and permit expansion and contraction.

7. In centrifugal pumps, an impeller, an 20 impeller casing, a sectional discharge casing, said impeller casing including a shaft bearing neck with bushing, a sectional line shaft casing, one of the sections of which is set over said bushing with a tight fit, a pump 25 head at the top of the discharge casing, a line shaft extending from the impeller to the pump head, means at the pump head for driving the line shaft, a series of line shaft bearing spiders rigidly located within the 30 discharge casing and having bearing portions for the shaft, said bearing portions

having upper and lower grooves with packing rings contained therein, and a sectional line shaft casing the ends of the sections of which lie in said bearing grooves in pressure 35 contact with the packing.

8. In centrifugal pumps, an impeller, an impeller casing, a sectional discharge casing, said impeller casing including a shaft bearing neck with bushing, a sectional line shaft 40 casing, one of the sections of which is set over said bushing with a tight fit, a pump head at the top of the discharge casing, a line shaft extending from the impeller to the pump head, means at the pump head for 45 driving the line shaft, a series of line shaft bearing spiders rigidly located within the discharge casing and having bearing portions for the shaft, said bearing portions having upper and lower grooves with packing 50 rings contained therein, and a sectional line shaft casing the ends of the sections of which lie in said bearing grooves in pressure contact with the packing, said pump head including a recessed portion to receive the 55 upper end of the uppermost line shaft casing section, and packing rings and gland nut for sealing the upper end of the uppermost line shaft casing section in said pump head recess.

JAMES HAMILTON JOHNSTON.
